UNITED STATES PATENT OFFICE.

ANDREW B. BOUGHAN, OF CHICAGO, ILLINOIS.

ELECTRICAL RAILROAD TRACTION APPARATUS.*

SPECIFICATION forming part of Letters Patent No. 698,099, dated April 22, 1902.

Application filed July 15, 1901. Serial No. 68,319. (No model.)

To all whom it may concern:

Be it known that I, ANDREW B. BOUGHAN, a citizen of the United States, residing at No. 40 Roslyn Place, in the city of Chicago, in the county of Cook and State of Illinois, have 5 invented a new and useful Improvement in Electrical Railroad Traction Apparatus, of which the following is a specification.

My invention relates to improvements in 10 electric railroad traction apparatus in which a removable protector operates in conjunction with a conductor conveying an electrical current to propel, light, or heat cars, whether passenger or freight; and the objects of my 15 improvements are, first, to provide an electric-traction conductor close under the surface of a railroad-bed or upon the surface, but so protected as not to endanger life or property; second, to afford facilities for easy 20 continuous removal of a section of the protector under a car; third, to replace the removed section of the protector continuously and simultaneously with the passage of the 25 car, so that not more than one section of the electric conductor is uncovered at a time and none of the conductor is exposed at either 30 end of a car, whether the car is in motion or standing still, the only portion of the conductor at any time uncovered being under the car at the moment of uncovering. I attain 35 these objects by the mechanism illustrated in the accompanying drawings, in which—

Figure 1 is a perspective view of the apparatus as it appears with a portion of a car 40 broken away; Fig. 2, a plane view of the part 45 of the apparatus close under the surface of the railroad-bed or upon the surface; Fig. 3, a vertical section of a part of the apparatus on the line 3 3 of Fig. 2; Fig. 4, a vertical section of a part of the apparatus on the line 4 4 of Fig. 2.

Similar letters refer to similar parts throughout the several views.

The motor *a* and the electrical collector or 45 shoe *b* constitute the mechanism conveying electric power for propulsion, light, or heat to the car from the conductor *f* on or close under the surface of the railroad-bed. In an inclosure of wood or other insulating ma-

terial under the surface of the railroad-bed 50 or on the surface is a cover or protector *d*, consisting of a block or strip of wood, at the back or side of which is a series of springs, each spring being marked *e*. These springs, except when pressed back, hold continuously 55 in place the protector or covering of the conductor *f*, which conveys along the entire length of the railroad the electrical supply or current for the various purposes of a traction system. Successive sections of the protector 60 *d d*, covering the electrical conductor *f*, are pressed back by the electrical collector or shoe *b* as a car passes along propelled by power from the conductor *f*. The collector or shoe *b*, attached to a car or train, is thus in continuous 65 contact with the source of electric power—namely, the conductor *f*. Pointed ends on the collector or shoe *b* facilitate the easy removal or pressing back of the sections of the protector *d d* and also help immediate replacement of the protector *d d* and replacement 70 being effected by the constant pressure upon the sections *d d* from the springs *e e*.

The top of the protector *d* forms a portion of the road-level except when a car is directly 75 above, at which time a section of the protector is pushed back under the upper cover of the box *c*. The hole or pipe shown in the bottom of the box *c* is an opening for drainage.

I am aware that prior to my invention electric railroad traction apparatus has been 80 made to prevent damage to life or property from the electric current. I therefore do not claim such an apparatus broadly.

What I do claim as my invention, and desire to secure by Letters Patent, is—

1. The combination in electric railroad traction apparatus of a laterally-movable non-conducting protector *d* or covering formed of a block or strip of wood or other suitable non-conducting material with an electric conductor *f* lying close to the surface of the railroad 90 all substantially as described.

2. The combination in electric railroad traction apparatus of an electrical collector 95 *b* together with a laterally-movable non-conducting protector *d* or covering formed of a block or strip of wood or other suitable non-

conducting material with an electric conductor *f* lying close to the surface of the railroad all substantially as described.

3. The combination in electric railroad traction apparatus of a protective covering for the working conductor consisting of a series of short lengths of wood or other non-conducting material having their ends interlocked

and adapted for lateral movement in combination with a conductor arranged near the surface of the railroad-bed.

ANDREW B. BOUGHAN.
